UNITED STATES PATENT OFFICE.

WILLIAM H. WETMORE, OF RALEIGH, N. C., ASSIGNOR OF TWO-THIRDS TO
THOMAS A. JONES AND AUGUSTUS W. KNOX, OF SAME PLACE.

DESK.

SPECIFICATION forming part of Letters Patent No. 317,253, dated May 5, 1885.

Application filed August 25, 1884. (No model.)

To all whom it may concern:

Be it known that I, WILLIAM H. WETMORE, a citizen of the United States, residing at Raleigh, in the county of Wake and State 5 of North Carolina, have invented certain new and useful Improvements in Desks, of which the following is a full, clear, and exact description.

The invention has reference to office and 10 similar desks for use of professional and business men and others; and its object is to effect the convenient arrangement within small space of a large number of compartments or pigeon-holes for the reception of papers, letters, and other articles, to be readily accessible 15 when required for reference.

To this end I provide a desk, which may be otherwise of ordinary or suitable construction, with a rotary cylinder journaled in bearings in the frame of the desk, so as to turn on a horizontal axis. This cylinder is placed, 20 preferably, at the rear of the desk just behind the writing table, and is divided into a number of compartments or pigeon-holes, in which 25 letters and papers may be distributed. By rotating the cylinder any desired compartment may be brought within reach.

It is to be observed that the cylinder is itself divided into compartments, and not a 30 series of trays pivoted to the heads of the cylinder. This latter construction has been adopted heretofore, the object of using pivoted trays being to allow them to swing as the cylinder revolves, and thus maintain the 35 horizontal position of the shelves or compartments; but it is objectionable for many reasons, among which may be mentioned increased cost, diminished compactness and strength, liability to get out of order, and the 40 like.

In my improved desk the compartments in the cylinder are, it is true, turned over at each revolution of the cylinder; but by providing suitable means for preventing the papers and 45 other articles from falling out or becoming disarranged otherwise when the cylinder is turned any practical difficulty on this account is obviated.

Upright in contradistinction to horizontal 50 compartment-cylinders have heretofore been combined with desks; but it is impossible to

arrange such cylinders so as to give the same convenient access to the same number of pigeon-holes or compartments as I give to my horizontal cylinder.

55

In carrying out the invention the cylinder is or may be divided into four equal sections by two partitions of wood or other material extending across the same at right angles to each other. Each section carries a group of 60 pigeon-holes formed, say, by shelves of wood one above the other at a suitable distance apart, the side walls of the pigeon-holes being slides of sheet metal or other material fitting removably in grooves sawed in the wooden 65 shelves. Each of the four groups of pigeon-holes is closed by a door hinged, preferably, to the top shelf and secured when closed by a spring-latch. A lightleaf spring may be employed in each pigeon-hole to bear downward 70 upon the pile of papers therein and prevent scattering when the cylinder is revolved.

To prevent rotation of the cylinder in case one side should be more heavily loaded than the other, a catch is provided which automatically engages the cylinder when one or the other group of pigeon-holes is brought into reach, and holds it in that position until released by hand.

The accompanying drawings, which form a 80 part of this specification, illustrate the best mode contemplated of carrying the invention into effect.

Figure 1 is a front view of a desk provided with the improvement; Fig. 2, a vertical cross-section of the cylinder. Fig. 3 is a partial view in horizontal section, showing the spring-bolt; and Fig. 4, a detail view on an enlarged scale, showing construction of the shelves.

The invention is shown applied to a desk, 90 A, which is or may be of any ordinary or suitable construction, having the usual writing-table, and provided with drawers, &c. At the back of the writing-table is a cylinder, B, of wood, journaled by means of short studs 95 b in the frame of the desk, so as to turn easily on a horizontal axis. Partitions B' divide the cylinder into a number of sections. As shown, there are two partitions, B', occupying planes at right angles to each other and making four 100 sections. The number of sections may be greater or less, as desired. In each section is

a group of pigeon-holes formed by shelves C and cross-pieces D. The shelves extend lengthwise of the cylinder, and are supported by the end walls thereof. These shelves are parallel with one partition, B', which forms the bottom of the group of compartments, and rearwardly extend to the other partition, which forms the back wall of the compartment. The shelves C are grooved on both sides at suitable intervals, and in the grooves are placed slides D of sheet metal, which form the side walls of the pigeon-holes. The slides D can readily be removed and inserted in different grooves, and thus the size of the compartments can be varied. The entire group of pigeon-holes or compartments is shut in by a door, E. The door is hinged, as shown, to the top shelf of the group, and fastened when shut by a spring-latch, F, whereby opening 20 of the door, and consequential spilling of the papers during the rotation of the cylinder, is prevented.

It is found in use that the rotation of the cylinder will not ordinarily cause any disarrangement of the papers in the various pigeon-holes; but as a greater precaution against such occurrence a light leaf-spring, d, is or may be screwed or otherwise secured to the top or to the bottom of each compartment, its free 30 end being arranged to bear against the papers therein. It will be seen that as the cylinder is rotated each group of compartments comes in succession within the reach of the user seated at the front of the desk, and that by 35 this device a great number of papers may be stored away and yet be readily accessible.

To prevent the cylinder turning of itself, as it might do if its load were unevenly distributed, a spring-bolt, G, is employed. It may 40 conveniently be placed, as shown, in the frame of the desk near the front, and arranged to engage with suitable sockets in the end wall of the cylinder. There should be one socket for each group of pigeon-holes, so that the cylinder 45 may be held stationary with any desired compartment in an accessible position.

The proportions of the cylinder and size of compartments may vary within wide limits. Supposing the cylinder to be twenty-eight 50 inches long (interior measurement) and thirty inches in diameter, each of the four sections could conveniently be divided into three tiers of compartments, seven in each row, the compartments being each four inches high, four 55 inches wide, and nine inches deep. Of course part of the holding capacity of the cylinder could be utilized for holding other articles besides papers—books, for example—and could be divided into compartments of any desired 60 size and shape.

The subdivision of the cylinder could be ac-

complished in other ways than that shown and described herein.

Other modifications in details of construction, which are given by way of example only, 65 may be made without departing from the spirit of the invention, and some of the improvements could be used without others.

I claim the new improvements herein described, all and several, to wit:

1. A desk or similar article of furniture provided with a revolving cylindrical portion mounted on a horizontal axis, and subdivided into pigeon-holes or compartments for the reception of papers and other articles, substantially as described. 70

2. A desk having a cylinder divided into pigeon-holes or compartments for reception of papers, &c., journaled in bearings in the frame thereof, with its axis of rotation horizontal, 80 and arranged at the back of the desk partly above and partly below the writing-table, substantially as described.

3. The combination, with the desk, of the horizontal revolving cylinder divided into sections by diametrical partitions, each section being subdivided into a number of compartments or pigeon-holes, substantially as described. 85

4. In a desk, and in combination with the desk-frame, a cylinder turning on a horizontal axis, and having its interior divided into groups of compartments adapted to be successively brought into reach by rotation of the cylinder, each group being provided with a door, substantially as described. 90

5. In a desk, the combination, with the cylinder divided into pigeon-holes or compartments and arranged to revolve on a horizontal axis, of the springs in the pigeon-holes or compartments for clamping the papers therein, 100 substantially as described.

6. The desk provided with a horizontal cylinder divided into pigeon-holes or compartments, and also provided with means, such as described, for preventing the papers in said 105 pigeon-holes or compartments being disarranged by the rotation of the cylinder, substantially as set forth.

7. The combination, with the desk-frame, of the cylinder divided into pigeon-holes or 110 compartments, and provided with latched doors for closing the ends of said pigeon-holes or compartments, and also with springs within the same, and a catch or bolt for preventing rotation of the cylinder except when desired, substantially as described. 115

In testimony whereof I affix my signature in presence of two witnesses.

WILLIAM H. WETMORE.
